[57] CLAIM

The ornamental design for a liquid crystal monitor for a video camera, as shown and described.

DESCRIPTION

FIG. 1 is a perspective view of the top, front and left side of a liquid crystal monitor for video camera showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a perspective view similar to FIG. 1 showing the liquid crystal monitor for a video camera mounted on a video camera;

FIG. 9 is a view similar to FIG. 8 with the monitor tilted about a horizontal axis;

FIG. 10 is a perspective view similar to FIG. 8 with the liquid crystal monitor pivoted about a vertical axis;

FIG. 11 is a perspective view of the top, rear and left side of a liquid crystal monitor for a video camera mounted on a video camera;

FIG. 12 is a perspective view of the top, front and left side of a modified liquid crystal monitor for a video camera showing our new design;

FIG. 13 is a front elevational view thereof;

FIG. 14 is a top plan view thereof;

FIG. 15 is a right side elevational view thereof;

FIG. 16 is a rear elevational view thereof; and,

FIG. 17 is a bottom plan view thereof.

The components shown in dashed line do not constitute part of the claimed design.
